UNITED STATES PATENT OFFICE.

MAX GRANT, OF PHILADELPHIA, PENNSYLVANIA.

DESIGN FOR A MIRROR.

• No. 39,507.

Specification for Design.

Patented Sept. 8, 1908.

Application filed July 22, 1908. Serial No. 444,873. Term of patent 3½ years.

To all whom it may concern:

Be it known that I, MAX GRANT, a citizen of the United States, residing at Philadelphia, in the county of Philadelphia and State of Pennsylvania, have invented a new, original, and ornamental Design for Mirrors, of which the following is a specification, reference being had to the accompanying drawing, forming part thereof.

The figure is an elevation of a mirror, composed of a main, central mirror surrounded

by four narrow mirrors forming a frame, in the corners of which are set metal squares carrying supporting brackets.

I claim—

The ornamental design for a mirror as shown and described.

MAX GRANT.
